UNITED STATES PATENT OFFICE.

GEORGE S. AXFORD, OF NORTHLVILLE, MICHIGAN.

HOBBY-HORSE.

No. 841,369.

Specification of Letters Patent.

Patented Jan. 15, 1907.

Application filed February 16, 1906. Serial No. 301,358.

To all whom it may concern:

Be it known that I, GEORGE S. AXFORD, a citizen of the United States, residing at Northville, county of Wayne, State of Michigan, have invented a certain new and useful Improvement in Hobby-Horses; and I declare the following to be a full, clear, and exact description of the invention, such as will enable others skilled in the art to which it pertains to make and use the same, reference being had to the accompanying drawings, which form a part of this specification.

This invention relates to hobby-horses for children's use, and has for its object a toy of the class described which, when not in use, can be easily taken apart and packed into small space and with similar ease put together, with its bracing members in such relation the one to the other that the entire structure is of equal rigidity with the permanently-assembled type, which occupies so much space that both when in the house and in transit it is greatly in the way, whereas the device of this application can be packed when taken apart into a space whose thickness does not exceed five or six inches.

In the drawings, Figure 1 is a side elevation of the horse. Fig. 2 is a sectional elevation showing the relation of the seat portion, brace portions, and side pieces. Fig. 3 is an enlarged detail of one of the brace members, the adjacent portions of the rockers being shown in dotted lines. Fig. 4 is an enlarged elevation of one of the binding-clips attached to the seat.

Each flank-piece consists of a unitary member A, whose surface is appropriately shaped and painted to represent a horse with the necessary harness-straps *a* about its head. Of these flank-pieces there are two, each mounted on a rocker C and spaced the one from the other by the seat and back portions, and the brace-pieces B and D, one near the front feet of the animal and the other near the rear feet. In appropriate parts of each flank-piece and on the inner face thereof are screws or bolts *k*, whose heads are just sufficiently raised above the surface of the wood to permit the entry therebetween of the binding-clips *m*, whose engaging faces are parallel with the flank-piece and which are rigidly secured to a back piece R and the seat portion S, one on each side of each.

When the back and seat portions, which are hinged to one another along their adjacent edges, so that when detached from the rest they may be spread out flat, are thus connected to the flank-pieces A, the screws *k* are tightened so as to bind firmly against the binding-clips. This in itself furnishes a structure of considerable rigidity, but in addition there are placed near the point of union of the fore and hind legs of each horse with its rocker brace-pieces B and D, which extend from one rocker to the other and whose locking-plates *b* similarly engage about bolts *d*, which may be tightened when the brace-pieces are slipped in place. These brace-pieces, in connection with the back and seat portions, give ample rigidity to the entire frame as thus assembled, and the forward brace-piece in addition serves as a convenient foot-rest.

In Fig. 2 the outlines of the back and seat portion when lifted from engaging position as regards their binding-clips are shown in dotted lines.

What I claim is—

1. In an article of the class described, in combination with side pieces and rocker members whereon the same are mounted, a removable back and seat portion adapted to be fixed therebetween, means fixed to the edges thereof and adapted to engage with complementary projections on each of said side pieces for rigidly securing said parts together, brace members extending from one rocker-piece to the other, and means whereby they may be similarly slipped into binding engagement with said rocker members, substantially as described.

2. In a hobby-horse, in combination with side pieces and rockers whereon the same are mounted, removable brace members extending from one of said rockers to the other and adapted to interlock therewith, a removable seat portion extending from the body portion of one side piece to the corresponding portion of the other side piece, and locking-clips rigidly attached to said seat portion and adapted to lock with complementary projections on said side pieces, substantially as described.

3. In a hobby-horse, in combination with side pieces provided with rocker-bases, independently-removable means whereby said

side portions are engaged and kept spaced from one another, said means comprising a seat portion adapted to removably interlock with its edges against complementary parts 5 of said side portions, and brace members similarly adapted to interlock with complementary portions of said rocker-bases, substantially as described.

In testimony whereof I sign this specification in the presence of two witnesses.

GEORGE S. AXFORD.
